UNITED STATES PATENT OFFICE.

EDOUARD SCHLAEPFER, FILS, AND LOUIS BLANC, OF LAUSANNE, SWITZERLAND,
ASSIGNORS TO SAID LOUIS BLANC.

PUMP.

1,258,471.

Specification of Letters Patent.

Patented Mar. 5, 1918.

Application filed December 8, 1916. Serial No. 135,720.

To all whom it may concern:

Be it known that we, EDOUARD SCHLAEPFER, Junior, and LOUIS BLANC, citizens of Switzerland, residing at Lausanne, Canton 5 of Vaud, in the Confederation of Switzerland, have invented certain new and useful Improvements in and Relating to Pumps, of which the following is a specification.

The invention consists of certain new and 10 useful improvements in pumps which may be applied to pumps of any size whatever and for any desired purpose: water-pumps, air-pumps and the like.

The improvement consists of having the 15 piston of the pump constructed so as to provide for a small axial displacement between the same and the piston-rod, means being employed to make the joint between the said rod and the piston tight whenever the rod 20 is moved in one direction and to have, on the contrary, the fluid (water, compressed air and the like) allowed to flow between the piston and the piston-rod whenever this said rod is moved in the opposite direction.

25 In the accompanying drawings, Figure 1 is a section of a piston constructed according to this invention, the piston-rod being moved in one direction.

Fig. 2 is a similar section when the piston-rod is moved in opposite direction.

Fig. 3 is an axial section of a spray-pump in which the invention is applied and in which the piston illustrated is a modification of that shown in Figs. 1 and 2, and Fig. 35 4 shows at an enlarged scale a part of this pump.

Referring to Fig. 1, *d* is the piston rod and *c* the piston which slides in a pump-cylinder *b*. The end of rod *d* carries a head member *e* of smaller diameter which may be screwed to the said rod *d* and which has a head-piece *e*¹. The piston *c* is provided centrally with a bore of different diameters and is placed on the said head member *e* the 45 diameter of which is less than the smaller diameter of the bore in the piston, so that the fluid to be pumped (water, compressed air or the like) may flow between the piston and the rod when the rod *d* is moved in the direction shown by the arrow *i* as shown in Fig. 1.

The end-portion of the rod *d* is fitted with a washer *d*¹ of leather or other suitable material, securing a tight joint between the rod

and piston whenever the rod *d* is moved in 55 the direction of the arrow *i* (Fig. 2).

When the piston-rod *d* is moved in the direction, as indicated by the arrow in Fig. 1, the piston *c* is moved by the head *e*¹ of the piece *e*, and as the said head *e*¹ is provided with suitable notches on its lower face, these notches permit the fluid which is compressed by the piston, to flow between the rod and the piston. The packing *f* of the piston may be pressed against the inner walls of the 60 cylinder *b* by the compressed fluid by means of suitable passages *e*¹ provided in the piston.

In the construction shown in Fig. 3 the piston *c* operates in an inner cylinder *b* of 70 a spray-pump or atomizer, having an outer cylinder *a*, co-axial to *b* and intended to contain the liquid to be sprayed. The said liquid is sucked through the pipe *b*¹ into the cylinder *b* of the pump whenever the piston-rod *d* is moved in the direction of the arrow shown in Fig. 2, the compressed liquid being 75 expelled through a nozzle formed of a tubular box *h*, screwed into the end of the cylinder *b* and of a cap *k* screwed on the 80 said tubular box *h*. The cap *k* is provided with a very small axial hole *k*¹ and contains an obturating implement *l* shown separately in Fig. 4. This implement is notched as 85 shown in Fig. 4 at *n* and *m* and has a circumferential groove *o*. The compressed liquid flows through the said notches and groove, causing the implement *l* to be rotated within the cap *k* and this rotation causes the said liquid to be sprayed as desired when ejected through the hole *k*¹.

The piston rod *d* is provided with an annular collar *d*² acting to limit its stroke in the direction of the arrow *i* as shown in Fig. 1.

This form of pump may be used for instance for the purpose of sprinkling flowers with water or for deodorizing purposes.

Claims:

1. In a pump and in combination, a cylinder, a piston fitting within the cylinder and having a central bore of different diameters, a piston rod, a head member secured in the end of the piston rod, passing through the bore of smaller diameter in the piston with 100 its extremity lying within the bore of larger diameter in the piston, and a washer surrounding the head member and adapted to 105

- bear against the adjacent surface of the piston to close the bore therethrough when the piston and piston rod are moved in one direction and to be moved away from the piston to open a passage-way through the bore in the piston when the same and the piston rod are moved in the opposite direction.
2. In a pump and in combination, a cylinder, a piston fitting within the cylinder and having a central bore of different diameters, a piston rod, a head member secured in the end of the piston rod, passing through the bore of smaller diameter in the piston with its extremity lying within the bore of larger diameter in the piston, a washer surrounding the head member and adapted to bear against the adjacent surface of the piston to close the bore therethrough when the piston and piston rod are moved in one direction

and to be moved away from the piston to open a passage-way through the bore in the piston when the same and the piston rod are moved in the opposite direction, and a packing ring lying within a recess provided therefor in the periphery of the piston, there being passage-ways making communication between the bore in the piston and the said recess in which the packing ring is located to permit the pressure within the cylinder to maintain the packing against the inner walls of the cylinder.

In testimony whereof we affix our signatures in presence of two witnesses.

EDOUARD SCHLAEPPER, FILS.
LOUIS BLANC.
